ABSTRACT: An actuator, coiled compression spring, and abutment surface or pair of stationary contact surfaces trap a contact roller. The spring shifts relative to the roller, assumes various contorted configurations, and whips the roller along actuator cam surfaces to stable roller positions. Also disclosed are means interlocking a shaft and switch actuator; a rotatable and axially movable switch actuator; and an actuator and shaft that snap together with means that prevent subsequent separation of the shaft and actuator.

**ELECTRICAL SWITCH AND COMBINATION
ELECTRICAL RESISTOR AND SWITCH**

This invention relates generally to electrical controls and, more particularly, to an electrical switch and to a combination variable resistance and electrical switch control.

The prior art includes many different types of electrical switches and variable resistance controls combined with such switches. In order to clarify the meaning of terminology used herein it is to be understood that the term "electrical control" is used generically to designate devices for controlling the current or voltage in an electrical circuit and that an "electrical switch" as well as a "combination variable resistance and electrical switch control" are a species of "electrical controls." It is well known that a snap-action switch must be capable of very rapidly making and breaking an electrical circuit and that the switch must be tease-proof, that is, the switch must be designed so that one or more movable contactors within the switch cannot be held in a neutral or center position by carefully controlling or manipulating the switch actuating member. By "neutral position" is meant a position where the contactor may momentarily engage and disengage a stationary contact with resultant arcing between the contact and consumption, e.g., burning, of contact surfaces in the switch. In recent years increased demands placed on switches have resulted in the realization that switches which were satisfactory for previous applications could not pass extended life tests and could not operate in a satisfactory manner over an extended period of time when required to switch heavy loads such as those encountered in modern consumer appliances and entertainment equipment. When used in modern high power requirement situations, it has been found that such switches permitted arcing to occur and destroy the movable and stationary contacts, that the temperature rise within the switch was too high due to high contact resistance, or that inadequate mechanical clearances existed between conductive elements within the switch. In addition to the increased loads that present day switches must handle, problems are presented by the fact that such switches must occupy no more volume than the prior art switches which they are to replace.

Much effort has been expended in trying to ascertain the optimum configuration for a bridging contactor in small, compact switch. One prior art design has used ball bearing type contactors, as illustrated for example in Ludwig Pat. No. 2,743,330 and Siiberg Pat. No. 3,032,620. Other designs have made use of knife blade or formed spring contactors as shown in Barden et al. Pat. No. 2,881,280 and dumbbell-shaped contact rollers. In each of these designs, spring means have been used to impart a snap-action movement to the contactor and to bias the bridging contactor into a stable position. In some instances, the bridging contactor has been a spring means whereas in other instances a separate spring element has been used to bias the bridging contactor. Each of these prior designs have required a relatively large number of parts that must be assembled together and this has resulted in a complex and expensive switch assembly.

One of the continuing problems in the industry has been the rapid destruction of either the bridging contactor or stationary contacts because of arcing between such contactor and stationary contact surfaces. Among other things, this has occurred because the movement of the contactor has not been sufficiently rapid, because of the movable contactor bouncing against the stationary contact surfaces as the switch is closed, and because of insufficient contact pressure between the bridging contactor and stationary contact surfaces which also contributes to objectionably high contact resistance, i.e., the electrical resistance between the bridging contactor and stationary contact surfaces.

In the particular species of electrical controls that include combination variable resistance and electrical switch controls, and particularly those of the type in which the control operator is a rotatable shaft as well as an axially movable switch actuator, the reliable and economical interconnection between

such shaft and switch actuator has also been a continuing problem. It will, therefore, be appreciated that it would be desirable to provide an improved economically producible electrical control wherein contactor bounce, arcing, burning and contact resistance within the control is substantially eliminated or reduced and yet wherein such control may be readily and inexpensively fabricated. In addition, it would be extremely desirable to provide means that would substantially prevent separation of an axially movable shaft from a switch actuator during normal operation of an electrical control.

Accordingly, it is an object of the present invention to provide a new and improved electrical control having the various desirable features set forth above. Another object of the present invention is to provide new and improved means that prevent separation of a shaft from a switch actuator. Still another object of the present invention is to provide a new and improved electrical control wherein a centrally positioned cam surface and spring means insure a balanced contact pressure between a bridging contactor and a pair of the stationary contact surfaces. A further object of the present invention is to provide a new and improved electrical control wherein an axially movable switch actuator is also rotatable so as to facilitate adjustment of a variable resistance control combined therewith. A still further object of the present invention is to provide a new and improved electrical control wherein spring means operate to provide fast and crisp movement of a bridging contactor relative to a pair of stationary contact surfaces. Further objects and advantages of the present invention will become apparent as the following description proceeds, and the features of novelty characterizing the invention will be pointed out with particularity in the claims annexed to and forming a part of this specification.

Briefly, the present invention is concerned with an electrical control which employs a bridging contactor that is movable between a first stable position wherein it engages at least one stationary contact surface and a second stable position wherein it is spaced from such contact surface. In a preferred embodiment, the bridging contactor is a cylindrical contact roller having a pair of end portions engageable with spaced stationary contact surfaces, a central portion engageable with a switch actuator, and portions between the central portion and end portions that are engageable by biasing means. Preferably, the biasing means is one or more coiled compression springs. In operation, a first cam surface on the switch actuator moves the contact roller against the bias of a spring. With continued movement of the switch actuator, the spring reaches a condition of maximum compression, the roller reaches a position of maximum lateral displacement, the spring decompresses, the roller moves to a labile neutral position, and the spring whips the contact roller along a second cam surface on the switch actuator. While the switch actuator is moving, the spring is free to shift tangentially relative to the contact roller and assume contorted configurations. With such shifting, the contact points between the roller and spring move and change the pressure angle between the contact roller and spring. With the changing pressure angle, the spring holds the contact roller against either an abutment or stationary contact surface while the contact roller is moving toward and away from positions of maximum lateral displacement and while the spring is compressed and subsequently decompressed. Then, as the spring whips the contact roller along the second cam surface, the spring assumes a changed contorted configuration and drives the contact roller to a stable position. In a preferred embodiment, means interlock the switch actuator and an axially movable shaft. In another embodiment a switch actuator is rotatable as well as axially movable. In still another embodiment, a switch actuator and shaft snap together, and means prevent the shaft from subsequently being pulled away from the actuator, preferably, such last-mentioned means comprise walls formed in an element which trap the actuator and prevent a pair of jaws on the actuator from releasing a reduced diameter portion of the shaft.

For a better understanding of the present invention, reference may be had to the accompanying drawings wherein the same reference numerals have been applied to like parts and wherein: FIG. 1 is an isometric view of a combination variable resistance and electrical switch control embodying the present invention; FIG. 2 is an exploded view of the control shown in FIG. 1 and includes a schematic representation of the location and direction of forces acting on one of the illustrated contact rollers when in a stable position thereof; FIG. 3 is a sectional view taken along lines III-III of FIG. 1; FIGS. 4-11 are fragmentary sectional views of the control of FIG. 1 and schematically illustrate the relative positions of a contact roller, spring, and switch actuator as the contact roller is moved between first and second stable positions thereof; FIG. 12 is a fragmentary sectional view of another embodiment of the present invention; FIG. 13 is an exploded isometric view of parts of the structure illustrated in FIG. 12; and FIG. 14 is an isometric view of a pair of contact rollers and a switch actuator in another embodiment of the invention.

Referring now to the drawings, and more particularly to FIG. 1, there is illustrated an electrical control generally indicated at 21 comprising a variable resistance control 22 and an electrical 23 secured together by locking ears 24 and 26 formed on a cover 27 of the variable resistance control. These ears interfit with notches 28, 29 formed in a switch housing 30. The variable resistance control 22 includes a threaded mounting bushing 31 suitable for insertion through an aperture in a mounting panel. A locating ear 32 secured to the control cooperates with a dimple or opening in such panel and prevents rotation of the electrical control 21 when a not shown locknut is threaded onto the bushing 31. In addition, the variable resistance control includes an insulating base 33 with a resistance element 34 secured thereto, a center collector 36, and a plurality of terminals 37-39 connected to the center collector and the ends of the resistance element as best shown in FIG. 2. A wiping contactor 41 is constrained to rotate with a contactor driver 42 and wipingly engages the center collector 36 and resistance element 34 intermediate the ends thereof. In order to move the driver 42, a shaft 43 is provided with a flatted portion 44 for drivingly engaging an aperture 46 in the driver. When the variable resistance control 22 is assembled, tabs 47, 49, 51 are folded over notches 52, 53, 54 in the insulated base 33 and the end 56 of the shaft 43 projects through an opening 57 formed in the bottom of the cover 27.

The switch 23 includes the previously mentioned housing 30, a pair of substantially identical helical compression springs 61, 62 a pair of substantially identical cylindrical contact rollers 63, 64, and a switch actuator 66 having a pair of double surfaced cams 67, 68 and a pair of jaws 69, 71 that interfit over the end 56 of the shaft 43. A pair of alignment arms 72, 73 on the switch actuator 66 are slidably received within a pair of slots 74, 76 formed in the housing 30 and facilitate assembly of the actuator and housing. Anchored in the housing 30 are four terminals 77, 78, 79, and 81. The upper ends of these terminals 77a, 78a, 79a, 81a provide spaced stationary contact surfaces within the housing that are bridged by the contact rollers 63 and 64 when the switch is in a closed switch condition. In order to retain the springs 61, 62 properly positioned in the housing 30 during operation, seats 82 and 83 formed in the ends walls of the housing receive the end portions 61a, 62a of the springs. Although the rear wall 84 of the cover 27 may be used to retain the contact rollers and springs within the housing 30 after assembly, it is preferred that a separate cover 86 be used for this purpose. A centrally disposed opening 87 in such cover permits the passage therethrough of the end 56 of the shaft and the jaws 69, 71 of the actuator 66. Means illustrated as shoulders 88, 89 and peripheral wall 91 formed on the switch housing 30 position the cover 86 on the housing.

Any suitable materials may be used to fabricate the above-mentioned parts of an electrical control embodying the invention and in the illustrated control 21, the terminals and con-

tact rollers were formed of an electrically conductive material, i.e., copper covered with a thin coating of silver to improve the solderability of the terminals and retard the formation of oxides on the contact surfaces. Phenolic or one of other materials too numerous to mention is used to fabricate the housing 30, essentially the only criteria for selection being that the housing be made of a material that will satisfactorily insulate the terminals 77, 78, 79, 81 from one another.

When the switch and variable resistance control are assembled together as shown in FIG. 3, the actuator 66 is axially movable along a line defined by the axis of rotation of the shaft 43, i.e., in the direction represented by the arrow A. With the contact rollers in the illustrated closed switch or first stable position, the actuator is in a corresponding first stable position with the cam faces 67a, 68a bearing against the contact rollers. In this position, the springs 61, 62 are at least slightly compressed and slightly contorted, i.e., held in a configuration other than single compression wherein adjacent convolutions of each spring proximate the contact surfaces 79a, 78a are spaced more closely together than the adjacent convolutions of the springs distal from such contact surfaces. While the contact rollers are in the first stable position, the jaws 69, 71 of the actuator 66 are received within the wall 92 of the driver 42 which is free to rotate relative to the actuator. However, the jaws 69, 71 of the actuator 66 are received within the wall 92 of the driver 42 which is free to rotate relative to the actuator. However, the jaws 69, 71 are spaced close enough to the wall 92 to prevent the jaws 69, 71 from opening to release the reduced diameter portion 56a of the shaft when an axial pullout force is applied to the shaft 43 as will be more fully described hereinafter in the detailed description of the embodiment illustrated in FIGS. 12 and 13.

The improved operating characteristics of the electrical control 21 will be best understood by now having reference to FIGS. 4-11 which clearly illustrate the sequence of operation of the control 21 as the contact rollers move from a first stable position shown in FIG. 4 to a second stable position shown in FIG. 8 and then move back toward the first stable position in response to movement of the actuator 66. FIGS. 4-11 have been presented for purposes of discussion only, and such figures are schematic representations of the control but it will be understood that the following description pertains to single or double pole, and single or double throw devices. The point P in FIGS. 4-11 generally represents a movable point of contact at the interface of the spring 62 and contact roller 64 and it will be appreciated that the pressure angle between the spring and roller, i.e., the angle defined by the intersection of a line passing through the point P and the center of the contact roller 64 with a horizontal line passing through the center of the contact roller, changes as the contact roller 64 moves between the two stable positions thereof. In other words, the point P moves as the contact roller moves between such stable positions. It will also be appreciated that in the control 21, two such contact points exist where the end convolutions 61b and 62b bear against the contact roller. In FIG. 2 these points have been identified on the contact roller 64 by the points P and P'.

In the first stable position shown in FIG. 4 the contact roller 64 is biased by the spring 62 into a wedge shaped area defined by the cam surface 67a, stationary contact surface 77a and not shown stationary contact surface 78a. In this position, the spring 62 biases contact roller 64 both downwardly against the stationary contact surfaces and laterally against the cam surface 67a. The center axis of the spring 62 as well as the upper and lower edges of the spring as viewed in FIG. 4 are curved, and to distinguish such curvature or nonuniform compression of the spring from a uniformly compressed configuration, the spring will be referred to as being "contorted" as well as compressed. As the actuator 66 is moved downwardly to the position illustrated in FIG. 5, the contact roller 64 is displaced outwardly along the stationary contact surface 77a to a position of maximum lateral displacement at which point the center of the contact roller is horizontally aligned with the apex of the cam. In this figure of the drawings, the spring has assumed a

second contorted configuration and is in a state of maximum compression. In addition, the pressure angle has increased since the end convolution 62b of the spring has shifted upwardly toward the cover 86 and effected an upward shift of the contact point P. During movement of the contact roller between the positions shown in FIGS. 4 and 5 the roller normally may either roll or slide along the stationary contact surfaces. In either case, good electrical continuity and a satisfactorily low contact resistance is maintained between the stationary contact surfaces and contact roller because of the downwardly directed bias of the spring 62.

Further movement of the actuator 66 to the position shown in FIG. 6 permits the spring 62 to decompress and reduce the amount of lateral displacement of the contact roller relative to the apex of the cam 67. During this decompression, spring 62 changes to a third contorted configuration and the pressure angle increases to a maximum value. Because of this change in pressure angle, i.e., tangential shift of the end convolution 62b of the spring relative to the contact roller 64, the contact roller is still held proximate to the stationary contact surfaces even through the apex of the cam 67 has moved to a position below a horizontal line passing through the center of the contact roller. When in the reduced displacement position of FIG. 6, the contact roller 64 is in a labile neutral position, it being understood that as it applies to the present illustrated embodiment, this term does not define the position of maximum lateral displacement of the contact roller 64 or the minimum compressed length of the spring 62. When the actuator 66 is moved an infinitesimal amount from the position of FIG. 6 to the position of FIG. 7, the contact roller 64 rapidly moves upwardly along the cam surface 67b. The movement of the contact roller 64 and spring 62 is surprisingly rapid and crisp, and the spring snaps from the contorted configuration shown in FIG. 6 to the configurations shown in FIG. 7 and shown in FIG. 8 wherein the contact roller 64 has attained the second stable position thereof. As the spring 62 snaps from the third configuration (FIG. 6) to the fourth configuration (FIG. 7), the end convolution 62b of the spring shifts tangentially relative to the contact roller and the point P shifts to a position below the center of the contact roller, i.e., the pressure angle becomes negative. As this occurs, the spring whips the contact roller upwardly away from the stationary contact surfaces while at the same time moving the contact roller transversely and upwardly along the cam surface 67b until the spring biases the contact roller into a wedge shaped area defined by the cam surface 67b and an abutment comprised by cover 86.

The foregoing description of FIGS. 4-7 also pertains to the operation of the control as the contact roller 64 moves from the second stable position shown in FIG. 8 through the various positions shown in FIGS. 9-11 until the first stable position is once again reached. However, it should be noted that the contact point P has shifted successively downwardly in FIGS. 9 and 10 and that the pressure angle becomes positive once again as the spring 62 whips from the labile neutral contorted configuration shown in FIG. 10 to the configuration illustrated in FIG. 11. As the spring biases the contact roller 64 toward the first stable position, the downwardly directed thrust of the spring greatly inhibits and in fact substantially eliminates bouncing of the contact roller as it engages the stationary contact surfaces.

A clear advantage of controls embodying this invention is that an extremely large movable contact surface is available for engagement with the stationary contact surfaces and yet such controls occupy no more space than the controls available heretofore. More specifically, the actual contact surface (per unit width of the stationary contact surfaces) available for consumption during the life of the control 21 is approximately 3.14 times the diameter of the contact roller 64. Although the foregoing description has not emphasized the fact that the contact roller 64 normally rolls along the stationary contact surfaces as it moves from the first to the second stable position, extensive tests have shown that normally the contact roller actually rolls along the stationary con-

tact surfaces. This condition contributes to extended contactor life since the contactor will then pry apart any welds along the interface of the movable and stationary contact surfaces as well as move a different surface portion of the contact roller 64 into engagement with the stationary contact surfaces on each successive actuation. After hundreds of thousands of actuations, when the movable and stationary contact surfaces have started to become worn, irregularities in the contact surfaces tend to provide a geared action and actually promote rolling of the contact roller along the stationary contact surfaces. A comparison of the changing relative positions of the contact roller and stationary contact surfaces in FIGS. 4-11 reveals that the contact roller makes and breaks contact with the stationary contact surfaces at two different locations along the stationary contact surfaces. This feature also contributes to longer life of the switch and satisfactory operation of the control 21 under high load or other adverse operating conditions. More specifically, the contact roller 64 breaks contact with the stationary contact surfaces at an outwardly displaced position of the contact roller and any arcing that occurs between the stationary and movable contact surfaces causes pitting or other degradation of the stationary contact surfaces in the region where the contact roller engages the stationary contact surfaces just prior to movement to the second stable position. Then, as the contact roller moves back to the first stable position, it initially engages the stationary contact surfaces along a region under the cam face 67a and then moves laterally toward the actuator and into the first stable position shown in FIG. 4.

The problem of insufficient pressure between the stationary and movable contact surfaces because of the presence of foreign matter between one of the stationary contact surfaces and the contact roller, or because of uneven contact pressure occasioned by other factors, is also overcome by the particular spatial relationship of the actuator, contact roller, and stationary contact surfaces. In FIG. 2, the arrows B, C represent the approximate direction of the forces applied to the roller 64 by the spring 62 in the first stable position. Similarly arrows D, E and F represent the reaction forces exerted by the stationary contact surfaces and the actuator upon the roller. Since the reaction forces D, E are applied to end portions of the roller, the reaction force F is applied to the central portion of the roller, and a dynamic or resilient biasing force B or C is applied to the roller between the central portion and each end portion thereof, the contact roller is self-balancing during operation. Thus, if a roughened contact surface or particle of foreign matter causes one end of the contact roller to seat abnormally on a stationary contact surface and causes the roller to be skewed relative to the two stationary contact surfaces coacting therewith, a substantially uniform contact pressure at both ends of the roller will still occur because the roller is free to pivot on the actuator in response to the resilient biasing forces exerted by the spring means. This feature assures a balanced and adequate contact pressure and concomitant low contact resistance.

It will of course be appreciated that many modifications may be made in the construction of electrical controls embodying the present invention that utilize the concept of the present invention and thereby attain the advantages thereof. For example, although the springs are illustrated as being coiled elements, other spring means, such as leaf spring, box springs, or spherical or circular resilient discs could be used to accomplish the objects of the present invention. Similarly, the bridging contactor could be an element other than a hollow cylinder although it is definitely preferred that the external configuration be such that the bridging contactor will readily roll across at least one of the stationary contact surfaces.

In FIGS. 12 and 13 a modified switch actuator 95, shaft 96, and driver 97 cooperate to permit axial plug-in assembly of the shaft and actuator. During assembly of the shaft 96 with the actuator 95, a tapered locking lug 101 is axially inserted between the jaws 98, 99 which resiliently yield and then snap together with the lips 103, 104 engaging the shoulder 106 of

the locking lug. This assembly is accomplished after the flatted portion 109 of the shaft has been inserted through a flatted aperture 111 in the driver 97. Upon movement of the actuator 95 to the second stable position thereof by movement of the shaft 96 outwardly relative to the control, the jaws 98, 99 move into a recess in the driver 97 defined by a wall 113. When continued or additional outward force is applied to the shaft 96, the jaws 98, 99 are prevented from releasing the lug 101 on the shaft by the wall 113. This antipullout feature, as previously mentioned, is also present in the embodiment illustrated in FIG. 1.

Still another modification is shown in FIG. 14 wherein the contact rollers 63, 64 have been shown in operable relationship with a switch actuator 116 fixedly secured to shaft 117. When the actuator 116 is formed integrally with the shaft 117 as illustrated, the material used in fabrication of the shaft and actuator must be an electrically nonconductive material such as nylon in order to prevent an electrical short circuit between the bridging contactors 63 and 64. Since the actuator 116 has only two continuous camming surfaces 116a and 116b, the actuator is continually rotatable with the shaft and also axially movable for moving the contact rollers between the first and second stable positions thereof. The flatted portion 119 of the shaft 117 interfits with a flatted driver that may be substantially the same as driver 42 or driver 97. This embodiment of the invention is particularly suitable in applications wherein an electrical control having a minimum number of parts is desired and yet wherein all of the advantages and desirable characteristics of the previously described embodiments are retained.

While there has been illustrated and described what is at present considered to be a preferred embodiment of the present invention and several modifications thereof, it will be appreciated that numerous changes and modifications are likely to occur to those skilled in the art, and it is intended in the appended claims to cover all those changes and modifications which fall with the true spirit and scope of the present invention.

What I claim as new and desire to be secured by Letters Patent of the United States is:

1. An electrical control comprising a housing, a first stationary contact surface fixedly positioned within the housing, a second stationary contact surface spaced from the first contact surface and fixedly positioned within the housing, an actuator having a cam surface and movable between at least two stable actuator positions along a predetermined path, a cylindrical contact roller movable to a first stable contact roller position wherein the contact roller is biased against said contact surfaces thereby to establish an electrical connection between said contact surfaces thereby to establish an electrical connection between said contact surfaces and movable to a second stable roller position wherein the contact roller is physically spaced from at least one of said contact surfaces, a spring means for wedging the contact roller between said cam surface and said contact surfaces, said spring means having a first portion thereof seated in the housing, a second portion bearing against and compressively engaging the contact roller, and a third resilient portion extending between said first and second portions, said resilient portion having energy stored therein while the contact roller is in the first stable position, initial movement of the actuator from a stable position thereof corresponding to said first contact stable roller position effecting movement of the contact roller along the cam surface and said contact surfaces to a position of maximum lateral displacement relative to the actuator, such movement of the contact roller causing the spring means to assume a condition of maximum compression, further movement of the actuator effecting further movement of the contact roller to a position of reduced lateral displacement corresponding to a first labile neutral position of the contact roller, such further movement of the contact roller causing the spring means to assume a partially decompressed condition, still further movement of the actuator causing the spring means to whip the contact roller to the second stable position thereof.

2. The electrical control of claim 1 wherein the second portion of the spring means maintains bearing contact with the surface of the contact roller at substantially two points thereby to reduce frictional forces between the contact roller and spring and permit the spring means to assume contorted configurations.

3. The electrical control of claim 1 wherein the second portion of the spring means shifts tangentially relative to the contact roller when the contact roller moves from the position of maximum lateral displacement to the position of reduced lateral displacement.

4. The electrical control of claim 1 wherein the pressure angle between the spring means and contact roller increases as the contact roller moves from the first stable position to the labile neutral position thereof.

5. The electrical control of claim 1 wherein the spring means is a coiled helical element having a central axis substantially normal to said predetermined path, the second portion of the spring means comprises an end convolution of the helical element, and the spring means has a contorted configuration when in the partially decompressed condition, said contorted configuration being defined by adjacent convolutions on the side of the spring means proximate to the stationary contact surfaces being disposed in closer proximity to each other than the adjacent convolutions on the side of the spring means distal from the stationary contact surfaces, the contorted configuration causing the spring means to cock as the contact roller reaches the first labile neutral position thereof and whip the contact roller to the second stable position thereof as the side of the spring means proximate to the stationary contact surfaces expand.

6. The electrical control of claim 1 wherein the control includes a rotatable and axially movable shaft, a resistance element, and a contactor wipingly engaging the resistance element and constrained to rotate with the shaft, axial movement of the shaft causing movement of the actuator along said predetermined path.

7. The electrical control of claim 6 wherein the actuator includes a pair of closed jaws disposed in an interlocking arrangement with the shaft and the control further comprises means for holding said jaws closed when a pullout force is applied to said shaft.

8. The electrical control of claim 7 wherein the shaft includes a locking lug, the jaws are closed around the locking lug, and the means for holding comprise a driver having an internal wall surrounding the jaws at least when a pullout force is applied to the shaft.

9. The electrical control of claim 6 wherein the actuator and shaft are formed integrally with each other and wherein the actuator moves axially and rotates in response to axial and rotary movement of the shaft.

10. In an electrical control, the combination of a housing, resistance means within the housing, a driver disposed in the housing, means carried by the driver for making wiping contact with the resistance means, at least one pair of stationary contact surfaces, at least one cylindrical contact roller movable between two stable positions and into and out of engagement with at least one of said stationary contact surfaces, a switch actuator engageable with the contact roller, spring means bearing against the contact roller for urging the contact roller against both of said stationary contact surfaces, and means for moving the driver relative to the resistance means and for moving the switch actuator between first and second stable positions.

11. The electrical control of claim 10 wherein said last mentioned means comprises a rotatable and axially movable shaft and the actuator includes a pair of jaws interfitting with said shaft thereby to permit rotation of the shaft relative to the actuator and to limit axial movement of the shaft relative to the actuator.

12. The electrical control of claim 10 wherein the driver is provided with a centrally located aperture, and a centrally located retaining wall, the means for moving the switch actuator comprises a rotatable and axially movable shaft extending

through the aperture, and the actuator includes a pair of jaws interfitting with the shaft, said jaws being disposed within the retaining wall when the contact roller is in at least one of the stable positions thereof whereby the retaining wall prevents the jaws from opening and releasing the shaft when a pullout force is applied to the shaft.

13. The electrical control of claim 10 wherein the last mentioned means comprise a rotatable shaft secured to the switch actuator and the switch actuator is provided with two continuous cam surfaces engageable with the contact roller, said actuator being rotatable and axially movable with said shaft.

14. An electrical control comprising at least one abutment surface, a pair of stationary contact surfaces, an actuator movable between first and second stable actuator positions, at least one cylindrical contact roller movable to a first stable roller position as the actuator is moved to the first stable actuator position and movable to a second stable roller position as the actuator is moved to the second stable actuator position, an spring means having an end portion seated within the housing and a bearing portion compressively engaging the surface of the contact roller, said spring compressively biasing

the contact roller against the pair of stationary contact surfaces in the first stable roller position and compressively urging the contact roller against said at least one abutment surface in the second stable roller position, said roller having a 5 pair of end portions engageable with the stationary contact surfaces, a central portion engageable with the actuator, a first portion between the central portion engageable with the actuator, a first portion between the central portion and one of the end portions engageable with the spring means, and a 10 second portion between the central portion and the other one of the end portions engageable with the spring means whereby the contact roller engages the stationary contact surfaces with a balanced contact pressure.

15. The electrical control of claim 2 wherein said two points 15 are spaced a distance greater than the diameter of said contact roller.

16. The electrical control of claim 15 wherein said cam surface and said second portion engage said contact roller at points spaced from each other and spaced from the points of 20 engagement of the contact roller and the contact surfaces.

UNITED STATES PATENT OFFICE
CERTIFICATE OF CORRECTION

Patent No. 3,600,533 Dated August 17, 1971

Inventor(s) JACK A. ENGLISH

It is certified that error appears in the above-identified patent and that said Letters Patent are hereby corrected as shown below:

In the Specification:

- Column 2, Line 3; Delete one of the words "to".
- Column 2, Line 71; After the word "pulled" and before the word "away", add the word "axially".
- Column 4, Line 18; Change the word "single" to ---simple---.
- Column 4, Lines 26, 27, & 28; Delete the sentence "However, the jaws 69, 71 of the actuator 66 are received within the wall 92 of the driver 42 which is free to rotate relative to the actuator."
- Column 4, Line 30; Change the word "wen" to ---when---.
- Column 5, Line 21; Change the word "through" to ---though---.
- Column 6, Line 6; Change the word "AFter" to ---After---.

In the Claims:

- Column 7, Lines 50 & 51; Delete the words "thereby to establish an electrical connection between said contact surfaces".
- Column 9, Line 19; Change the word "an" to ---and---.

Signed and sealed this 29th day of May 1973.
